W. H. HARRISON.
TELEPHONE EXCHANGE SYSTEM,
APPLICATION FILED MAY 9, 1918.

1,337,471.

Patented Apr. 20, 1920.

Inventor:
William H. Harrison.
by *J. E. Roberts*
Atty.

UNITED STATES PATENT OFFICE.

WILLIAM H. HARRISON, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,337,471.

Specification of Letters Patent.

Patented Apr. 20, 1920.

Application filed May 9, 1918. Serial No. 233,450.

To all whom it may concern:

Be it known that I, WILLIAM H. HARRISON, a citizen of the United States, residing at Brooklyn, in the county of Kings, 5 State of New York, have invented certain new and useful Improvements in Telephone-Exchange Systems, of which the following is a full, clear, concise, and exact description.

10 This invention relates to telephone exchange systems, and more particularly to such systems of the central energy type.

The object of this invention is to provide improved signaling means for such systems.

15 In accordance with this invention a central office link circuit is provided with a relay which is energized upon each energization of the link circuit supervisory relay, and deenergized upon each deenergization.

20 thereof, and a third relay which is energized upon the deenergization of the supervisory relay, and with interrupter mechanism which is connected in circuit with a signaling device associated with the link circuit 25 when all three of the relays are energized.

For a more complete understanding of this invention, reference should be had to the following description considered in connection with the accompanying drawing 30 illustrating one embodiment thereof.

As shown in the drawing two telephone lines A and B terminate at a central office at which is located a link circuit C for connecting together lines for conversation. It 35 will be understood, of course, that many lines similar to A and B may terminate at the central office, and that a number of link circuits similar to C may and usually are provided for interconnecting such lines.

40 However, for the purpose of simplicity, only the two lines and the one link circuit are shown. It is thought that the nature of this invention is such that it will be thoroughly understood from a description of the 45 operation of the system disclosed in the drawing, and it will be so described.

Subscriber A, in initiating a call, removes the receiver from the switchhook, thereby causing the lighting of line lamp 5. The 50 operator, observing the lighted condition of this line lamp 5, inserts answering plug 6 into line jack 7, thereby causing the normally closed contacts of the jack 7 to be opened to remove the ground connection 55 and the line lamp connection from the line,

thereby to efface the line lamp. Supervisory relay 8 also operates upon the connection of the answering plug with the line jack, and in operating, causes the operation of relay 9 over a circuit from battery 60 through the winding of relay 9, contact 10 thereof, alternate contact of relay 8, sleeve contacts of the plug 6 and the jack 7 and resistance 12 to ground. Relay 9, in operating, completes a locking circuit for itself 65 which may be traced from battery through the winding of relay 9, contact 13 thereof, contact 14 of relay 15, sleeve contacts of the plug 6 and the jack 7 and resistance 12 to ground. The operator may now actuate 70 listening key 16 to connect the telephone set with the talking strands of the cord circuit C. Upon being advised that connection is desired with the line of subscriber B, the operator restores listening key 16 to 75 normal position and inserts plug 20 into jack 21, whereupon calling supervisory lamp 22 is lighted over a circuit from battery through the lamp 22, contact of calling supervisory relay 23, sleeve contacts of 80 the plug 20 and the jack 21 and resistance 24 to ground. The insertion of the plug into the jack also causes the disconnection of the line lamp from the line. The called-for subscriber may now be signaled by actuating ringing key 25 to connect a source of 85 ringing current 26 with the line for operating the usual call bell at the station, after which the ringing key may be restored to normal position. Subscriber B, in responding to the operation of the call bell, removes the receiver from the switchhook, thereby 90 causing the operation of the calling supervisory relay 23 which opens the circuit of and extinguishes calling supervisory 95 lamp 22.

At the conclusion of the conversation, the subscribers restore the receivers to the switchhooks, thereby causing the deenergization of the supervisory relays 8 and 23, 100 which in releasing their armatures, close operating circuits for answering supervisory lamp 27 and calling supervisory lamp 22. These lamps are thereupon lighted to furnish disconnect signals. The operator may 105 then withdraw the plugs from the jacks, restoring all apparatus to normal condition.

Assuming, however, that subscriber A, after finishing the conversation with subscriber B and before the operator has with- 110

drawn plug 6 from the jack 7, desires to initiate another call, the removal of the receiver from the switchhook after its restoration thereto, causes the intermittent operation 5 of the answering supervisory lamp 27. This intermittent operation of the answering supervisory lamp 27 which serves as a recall signal to the operator, is brought about in the following manner. Upon the 10 restoration of the receiver to the switchhook by subscriber A and the consequent de-energization of the answering supervisory relay 8, relay 15 operates over a circuit from battery through the normal contact of 15 listening key 16, winding of relay 15, contact 30 thereof, contact 31 of relay 9, normal contact of relay 8, sleeve contacts of the plug 6 and the jack 7, and resistance 12 to ground. Relay 15, in operating, establishes 20 a locking circuit for itself which may be traced from battery through the normal contact of the listening key 16, winding of relay 15, contact 32 thereof, sleeve contacts of the plug 6 and the jack 7, and resistance 25 12 to ground. The establishment of this locking circuit renders relay 15 independent of the condition of either the answering supervisory relay 8 or the relay 9. The opening of contact 14 of relay 15 interrupts the 30 locking circuit of relay 9 which now releases its armatures. The closure of contact 33 of relay 15 connects interrupter 35 with the open contact 31 of relay 9. The subsequent 35 energization of the supervisory relay 8 causes the operation of relay 9 over a circuit from battery through the winding and contact 10 of relay 9, alternate contact of relay 8, sleeve contacts of the plug 6 and the jack 7 and resistance 12 to ground. Contact 13 of relay 9 is closed before contact 10 40 opens, so that a holding circuit for relay 9 is established upon its energization. This holding circuit may be traced from battery through the winding and contact 13 of relay 45 9, contact 34 of relay 15, alternate contact of relay 8, sleeve contacts of the plug 6 and the jack 7, and resistance 12 to ground. The closure of contact 31 of relay 9 connects the interrupter 35 in circuit with the lamp 27, 50 thereby causing the intermittent operation of this lamp.

The operator, observing the intermittent lighting of the supervisory lamp 27 actuates listening key 16 to connect the operator's telephone set with the talking strands of the cord circuit. Upon the operation of 55 this listening key 16, the normally closed contact thereof is opened, whereupon relay 15 is de-energized. Relay 15, in releasing its 60 armatures, disconnects the interrupter 35 from circuit relation with the lamp 27, thereby stopping the intermittent lighting of this lamp. Relay 15, in releasing, also causes the de-energization of relay 9, but this 65 relay, immediately upon releasing its arma-

tures, establishes its original energizing circuit. Upon this re-energization of relay 9, its locking circuit is established in the manner before described.

What is claimed is:

1. A telephone exchange system comprising a telephone line, a link circuit connected therewith, a supervisory relay for the link circuit, a second relay operating upon the energization of the supervisory relay, a 75 third relay energized upon the de-energization of the supervisory relay to release the second relay, a signaling device, and interrupter mechanism connected in circuit with the signaling device by the subsequent operation of the second relay when the supervisory relay is energized.

2. A telephone exchange system comprising a telephone line, a link circuit connected therewith, a supervisory relay for the link circuit, a second relay operating upon the energization of the supervisory relay, a 85 third relay energized upon the de-energization of the supervisory relay to release the second relay, a signaling device, interrupter mechanism, and an operating circuit for the signaling device and interrupter mechanism established upon the subsequent operation of the second relay and including engaged contacts of the energized second and third 90 relays.

3. A telephone exchange system comprising a telephone line, a link circuit connected therewith, a supervisory relay for the link circuit, a second relay operating upon the 100 energization of the supervisory relay, a third relay, a locking circuit for the second relay established upon the operation thereof and including a contact of the de-energized 105 third relay, an energizing circuit for the third relay established upon the de-energization of the supervisory relay and including a contact of the operated second relay thereby to release the second relay, a signaling 110 device, and interrupter mechanism included in circuit with the signaling device by the subsequent operation of the second relay when the supervisory relay is energized.

4. A telephone exchange system comprising a telephone line, a link circuit connected 115 therewith, a supervisory relay for the link circuit, a second relay operating upon the energization of the supervisory relay, a third relay, a locking circuit for the second relay established upon the operation thereof 120 and including a contact of the de-energized third relay, an energizing circuit for the third relay established upon the de-energization of the supervisory relay and including a contact of the operated second relay thereby to release the second relay, a signaling 125 device, interrupter mechanism, and an operating circuit for the signaling device and interrupter mechanism established upon the subsequent operation of the second relay and 130

including engaged contacts of the energized second and third relays.

5. A telephone exchange system comprising a calling telephone line, a link circuit connected therewith, a supervisory relay for the link circuit energized upon the closure and deenergized upon the opening of the telephone line, a second and a third relay for the link circuit, an energizing circuit for the second relay closed upon the first energization of the supervisory relay, a locking circuit for the second relay completed upon the energization thereof and including a contact of the deenergized third relay, an energizing circuit for the third relay established upon the deenergization of the supervisory relay and including a contact of the energized second relay, the energization of the third relay opening the locking circuit of the second relay, a locking circuit for the third relay completed upon the energization thereof, a signaling device, interrupter mechanism, and an operating circuit for the signaling device and interrupter mechanism

completed upon the second energization of 25 the supervisory relay and including contacts of the energized second and third relays.

6. A telephone exchange system comprising a telephone line, a link circuit connected 30 therewith, a supervisory relay for the link circuit energized upon the closure and deenergized upon the opening of the telephone line, a second relay energized upon the energization and deenergized upon the deenergization of the supervisory relay, a third 35 relay energized upon the energization of the second relay when followed by the deenergization of the supervisory relay, a signaling device and interrupter mechanism, and 40 an operating circuit therefor established when all three relays are energized and including contacts of the second and third relays.

In witness whereof I hereunto subscribe 45 my name this 3rd day of May, A. D. 1918.

WILLIAM H. HARRISON.
